CLAIM

The ornamental design for a chair rest separation apparatus, as shown and described.

DESCRIPTION

FIG. 1 is a bottom view of the open invention.

FIG. 2 is a perspective view of the open invention shown mounted.

FIG. 3 is a front elevation view of the closed invention.

FIG. 4 is a front elevation view of the open invention.

FIG. 5 is a perspective front view of the open invention, shown mounted.

FIG. 6 is a side perspective view of the closed invention.

FIG. 7 is a side perspective view of the invention, mounted in an alternative manner; and,

FIG. 8 is a rear perspective view of the open invention, mounted for display.

The invention has an “open” and a “closed” position. Shown in FIG. 4, the open position is the position in which the invention is unfolded so the flaps on its bottom can clasp an armrest. In the closed position, best seen in FIG. 3, the invention folds flat. The invention is used in the open position, and stored in the closed position.
